US0D1084860S

(12) **United States Design Patent** (10) **Patent No.:** **US D1,084,860 S**
(45) **Date of Patent:** **** Jul. 22, 2025**

(54) **CONTAINER FOR PACKAGING**

(71) Applicant: **YONWOO CO., LTD.**, Incheon (KR)

(72) Inventor: **Na Eun Song**, Incheon (KR)

(73) Assignee: **YONWOO CO., LTD.**, Incheon (KR)

(**) Term: **15 Years**

(21) Appl. No.: **29/902,258**

(22) Filed: **Sep. 11, 2023**

(30) **Foreign Application Priority Data**

Mar. 30, 2023 (KR) 30-2023-0012015

(51) **LOC (15) Cl.** **09-03**

(52) **U.S. Cl.**

USPC **D9/504**

(58) **Field of Classification Search**
